UNITED STATES PATENT OFFICE

WILLIAM GINGRICH, OF STILES, IOWA.

ADJUSTABLE TAILINGS-BOARD FOR THRESHERS AND SEPARATORS.

SPECIFICATION forming part of Letters Patent No. 650,811, dated May 29, 1900.

Application filed October 26, 1899. Serial No. 734,901. (No model.)

To all whom it may concern:

Be it known that I, WILLIAM GINGRICH, a citizen of the United States, residing at Stiles, in the county of Davis and State of Iowa, have 5 invented a new and useful Adjustable Tailings-Board for Grain Threshers and Separators, of which the following is a specification.

My object is to provide means for adjusting the tailings-board of a riddle in a grain 10 thresher and separator while the machine is in operation. Heretofore it has been necessary to stop the work in order to adjust the board as required to prevent grain from being blown out over the board. The condition 15 and weight of grains vary, and when it is discovered that the air-blast carries light grains out over the tailings-board with chaff such loss of grain can be prevented by adjusting the position of the tailings-board relative to 20 the frame that carries the screens. I have provided means for changing the angle of the tailings-board and also for raising and lowering it; and my invention consists in the construction, arrangement, and combination of 25 parts, as hereinafter set forth, pointed out in my claims, and illustrated in the accompanying drawings, in which—

Figure 1 is a perspective view showing my invention applied to the rear end portion of 30 a frame adapted to carry screens as required in practical use in a thresher and separator. Fig. 2 is an enlarged perspective view of one of the metal board - bearers adapted to be 35 adjustably connected with the frame as required for supporting the tailings-board at different angles and different elevations at different times. Fig. 3 is an enlarged perspective view of one of the metal end pieces having an integral rack adapted to be fixed 40 to the end of a tailings-board and combined with metal board-bearers and the frame of a riddle as required to raise and lower the board while the machine is in operation.

The letters A and A² designate the parallel 45 wooden sides of the frame of a riddle-carrier.

B and B² are mating metal bearers adapted to be adjustably connected with the ends of the frame to support a tailings-board. Each 50 has a vertical groove c, an integral curved and slotted arm d, and a perforated lug f and is connected with the outside face of one of the parallel sides of the frame by means of

clamping-crews h, extended out through perforations in said sides and nuts i on the ends of the screws, as shown in Fig. 1. 55

J and J² are mating metal plates adapted to be fixed on the ends of a tailings-board K. Each has an integral rack m and one end provided with a tongue c', adapted to fit in the groove c of one of the metal board-bearers, 60 and the other end portion tapered and perforated and adapted to overlie a correspondingly-tapered end of the board K and to be fixed thereto by means of bolts and nuts, as required to produce a scarf-joint. 65

N is a rotatable rod extended through the perforated lugs f. Pinions o, fixed to the rod, engage the rack m. A ratchet-wheel r and a crank-handle s are on one end of the rod, and a pawl y is pivoted to the plate A to engage the ratchet-wheel. 70

By relaxing the force of the clamping-screws h the board-bearers B and B² can be readily adjusted as required to change the angle of the tailings-board K, and by rotating the rod 75 N the board can be readily raised and lowered, to be retained at any elevation desired, by means of the pawl and ratchet, and it is obvious such adjustment can be advantageously made while the machine is in operation. 80

Having thus described the construction, application, and operation of my invention, its practical utility will be readily understood by persons familiar with the art to which it pertains, and 85

What I therefore claim as new, and desire to secure by Letters Patent therefor, is—

1. A metal bearing for an adjustable tailings-board in a thresher, consisting of a metal 90 casting having a straight groove extending from top to bottom, an integral curved and slotted arm extending laterally at one side of said groove and an integral perforated support for a shaft extending in the opposite direction from the other side of the groove, flat plates adapted to be fixed to the end portion of a tailings-board, each having an integral rack extending vertically on its outside face and an integral tongue extending from top to 95 bottom at one end adapted to enter said groove and a shaft having fixed pinions adapted to engage said racks as shown and described, for the purposes stated. 100

2. An adjustable tailings-board for threshers and separators comprising two mating metal board-bearers each having a groove to admit the end of a board, a curved and slotted arm for adjustably connecting it with the frame of a riddle-carrier and a perforated lug for supporting a rotatable rod, two mating metal ends for a wooden tailings-board each having an integral rack and a tongue at one end to enter a groove in one of the metal

board-bearers, a rod having fixed pinions to engage the racks, a ratchet-wheel and crank-handle on the end of the rod and a pivoted pawl to engage the ratchet, arranged and combined to operate in the manner set forth for the purposes stated. 15
